United States Patent Office.

HENRY YORK, OF SMITH'S LANDING, NEW JERSEY.

Letters Patent No. 92,555, dated July 13, 1869.

IMPROVEMENT IN STEERING-APPARATUS.

The Schedule referred to in these Letters Patent and making part of the same.

To all whom it may concern:

Be it known that I, HENRY YORK, of Smith's Landing, in the county of Atlantic, and State of New Jersey, have invented a new and improved Steering-Gear; and I do hereby declare that the following is a full, clear, and exact description thereof, which will enable those skilled in the art to make and use the same, reference being had to the accompanying drawings, forming part of this specification, in which—

Figure 1 is a vertical cross-section of my invention through the line $x x$, fig. 2.

Figure 2 is a plan view of the invention.

Similar letters of reference indicate corresponding parts.

The object of this invention is to provide a simple and effective steering-apparatus for vessels, and which combines many advantageous features, as will be hereinafter explained.

The invention consists, in general terms, in the employment of two drums arranged side by side, and provided with toothed rims or cog-wheels, which are engaged by a pinion on the shaft of the steering-wheel, and the drums and steering-wheel having bearings, in any suitable uprights, of timber or metal, which uprights may be affixed to the tiller and arise therefrom, thus characterizing the whole apparatus as a "travelling-wheel" to "standing-wheels," so called.

By the employment of two drums instead of one, as heretofore, I dispense with the steering-tackles which are necessary to obtain sufficient purchase on the tiller, and in dispensing with the said tackles, obviate the use of a long "fall," or rope, which, from the number of turns it makes on a single drum in putting the helm "hard up" or "hard down," the turns are liable to ride or overlap each other.

In dispensing with the tackles, or such double or single-rope purchases, I am enabled to employ chains instead of ropes, whereas the employment of chains with the ordinary single drum and tiller, and deck-blocks, has been attempted and abandoned long ago, as objectionable, from the liability of the chains to jam in the blocks.

By my invention, however, as only one single block is used for each chain, and those being attached to the tiller in such a manner that the chains will ride on only a quadrant of the sheave, there is no liability of the chain fouling or jamming in the block, as will be obvious to mariners and others skilled in such mechanism.

By the employment of decreasing gear, that is, a

cog-wheel operated by a pinion on the steering-wheel shaft, I gain sufficient purchase to operate the rudder without the aid of any further or accessory gear, as tackles and the like.

My invention will be better understood by reference to the drawings, where

A is a steering-wheel of the usual construction, mounted on a metal shaft, a , which bears a small pinion b , engaging with the toothed rims or cog-wheels d , on the drums B B, or the shafts thereof.

The shaft a , and the shafts or gudgeons of the drums B B, are afforded bearings in broad uprights C C, which, in the drawings, are shown affixed to and arising from the tiller D.

Each of the tiller-ropes or chains (preferably the latter) is attached to its respective drum, and leads down through a tiller-block, f, containing a single sheave, and thence to some suitable device, as an eye-bolt, g, affixed in the deck beyond the travel of the tiller D.

The tiller-rope or chain thus consists of a single part, and the number of turns which is required to be wound on either drum to put the tiller "hard-a-port" or "hard-a-starboard," will not be more than two or three turns with drums of the usual diameter, thus enabling the tiller to be rapidly operated, while the purchase obtained by the pinion b , of less diameter than the cog-wheels d , enables the tiller to be operated with the application of the same or less power to the steering-wheel than with the ordinary single drum and tiller-tackles.

The pinion and cog-wheels may be made with V-shaped faces to operate as friction-gearing, if desired.

Having thus described my invention,

I claim as new, and desire to secure by Letters Patent—

The arrangement, upon the tiller D, of the uprights C C, tiller-blocks f f, and drums B B, carrying the cog-wheels d d adapted to engage with the pinion b , upon the shaft a of the steering-wheel, also having its bearings in the uprights, whereby a travelling steering-gear is produced, as herein shown and described.

The above specification of my invention signed by me, this 9th day of October, 1868.

HENRY YORK.
